UNITED STATES PATENT OFFICE.

JOHN NEWBERRY REYNOLDS, OF GREENWICH, CONNECTICUT, ASSIGNOR TO
WESTERN ELECTRIC COMPANY, INCORPORATED, OF NEW YORK, N. Y., A
CORPORATION OF NEW YORK.

TELEPHONE-EXCHANGE SYSTEM.

1,375,230.

Specification of Letters Patent. Patented Apr. 19, 1921.

Application filed March 29, 1917. Serial No. 158,190.

To all whom it may concern:

Be it known that I, JOHN NEWBERRY REYNOLDS, a citizen of the United States, residing at Greenwich, in the county of Fairfield and State of Connecticut, have invented certain new and useful Improvements in Telephone-Exchange Systems, of which the following is a full, clear, concise, and exact description.

This invention relates to automatic switching apparatus for telephone exchange systems, and has for its object the provision of apparatus of this type which will be compact in structure, efficient in operation, and low in the cost of production and maintenance.

In accordance with the general objects of this invention, means are provided whereby a large number of multiple contacts accessible to any one of a number of brushes may, without the use of bank or connecting wires, be grouped into a space of such area that any one of the brushes may be moved into engagement with any multiple contact within the bank in steps of a length possible to attain easily and within a period of time found to be desirable and practical in such systems. More specifically, the invention comprises a switching mechanism in which a plurality of layers of multiple contacts are mounted in superimposed relation to each other and brushes are provided, each adapted to be selectively moved to the said layers and transversely to the contacts of a selected layer.

A convenient form of unit layer, and one which is believed to be novel, may be composed of a plurality of longitudinally extending conductors insulated from each other, and divided into sets. More specifically, the multiple contact member may comprise a fabric consisting of bare wires forming the warp and insulating strips forming the woof, the spacing and weaving of wires and insulating strips being such as to divide said wires into sets of contacts. The web or fabric thus formed is secured to a metal mounting plate by insulating means which leaves the contact portions of the wires exposed for engagement by brushes. The metal mounting plate forms a strong and convenient means for mounting the strips and prevents cross-talk between conductors.

Other features of this invention relate to the construction and mounting of the multiple contact members whereby they will be accessible to the maximum number of brushes; the construction of the apparatus for rendering the multiple contact members adjustable and removable and readily accessible for adjustment or removal; and the method of mounting the multiple contact members to prevent the accumulation of foreign substances, such as dust or metal particles thereon. The apparatus is made accessible to the maximum number of brushes by making the contact portions of the multiple contact members sufficiently wide so that they may be traversed simultaneously by two independently movable brush sets, and so mounting said contact members that they may be accessible to brush sets mounted upon either side thereof. The protection of the contacts is obtained by the construction and mounting of the multiple contact members in such a manner that the contacts are exposed only on the under side of said contact member.

A novel brush operating mechanism for moving a brush set in two directions in lines at right angles to each other, and in steps differing in length, is also included among the features of this invention. Preferably a single operating mechanism is provided for moving the brush set in one direction in steps of one length, and in another direction in steps of a different length. Details of the construction of the switch operating mechanism for making the change-over from one length of step to the other and for changing the direction of movement of the brush set are also believed to be new.

The details of the construction of the multiple contact member for providing simple, rigid and convenient terminals for the conductors are also features of this invention.

In the drawings illustrating this invention,

Figure 1 is a view in side elevation of a brush operating mechanism embodying features of this invention;

Fig. 2 is a detail sectional view taken upon line 2-2 of Fig. 1;

Fig. 3 is a sectional view taken upon line 3-3 of Fig. 1;

Figs. 4 and 5 are perspective views of parts of the brush operating mechanism;

Fig. 6 is a view in perspective of a brush carriage and brushes;

Fig. 7 is a view in side elevation, with parts broken away, of a multiple contact bank embodying features of this invention;

Fig. 8 is a sectional view of the bank showing the face of one of the multiple contact strips and the relation of the brushes thereto;

10 Fig. 9 is a view of a portion of the end of one of the multiple contact strips;

Fig. 10 is a transverse sectional view of one of the multiple contact strips;

15 Fig. 11 is a perspective view showing tails of the multiple contact strip; and

Fig. 12 is a view showing the manner in which the apparatus embodying the features of this invention may be wired in a system.

20 In the following detailed description of this invention reference will first be made to the contact bank construction and the details thereof as illustrated in Figs. 7, 8, 9, 10 and 11.

25 Referring first to Figs. 7 and 8, the reference numerals 5, 5 designate a plurality of multiple contact strips supported between side frame members 6, 6, 6, 6, which side frame members are secured at their ends to

30 top and bottom frame members 7, 7.

Each of the multiple contact strips 5, 5 is the same as illustrated and claimed in a co-pending application of the same inventor, Serial No. 180,348, filed November 9, 1916.

35 As shown in the drawings each of the strips 5, 5 comprises a plurality of bare wires, 8, 8, 9, 9, and 10, 10 arranged in groups of three, wires 8, 9 and 10 appearing in each group. These wires 8, 8, 9, 9 and

40 10, 10 compose the warp of a fabric, the woof of which is composed of insulating strips 12, 13, 14, 15, etc., woven between the separate strands to displace portions 20, 20 thereof into a brush contacting position, as

45 more clearly shown in Fig. 11. The weaving and arrangement of the insulating strips 12, 13, 14, 15, etc., is such that the adjacent wires 8, 9 and 10 of each set will have their displaced portions 20, 20 longitudinally separated from each other, while the corresponding wires of each set will be displaced in the same line transverse of the strip. Thus the conductors 8, 8, 8 of the several sets will pass over the strip 12, under

50 the strips 13, 14, and over the strip 15, etc. The conductors 9, 9, 9 will pass under the strip 12, over the strip 13 and under the strips 14 and 15, and over the next strip beyond 15 in the contact strip. The wires 10,

55 10, 10 will pass under the strips 12 and 13, over the strip 14, and under strip 15 and the next strip beyond to appear again on the surface at the third strip beyond the strip 14. The insulating strips 12, 13, 14, 15, etc.,

60 are each provided at their edges with a plu-

rality of notches 21, 21 as clearly shown in Fig. 11, these notches serving to seat the conductors or wires and maintain them separated. These notches 21, 21 are provided in the insulating strips only at the portions where the conductors pass over them; that is, the strip 12 will be notched only at the portions where the conductors 8, 8 pass over it, the strip 13 at the portions where the conductors 9, 9 pass over it and the strip 14 at the portions where the conductors 10, 10 pass over it.

The web or fabric thus formed by the bare wires and insulating strips is secured to a mounting plate 23; preferably of thin sheet metal, by means of heat hardenable insulating material and in such a manner as to leave the displaced portions of the wires bare. The plate 23 is provided at one end with an enlarged portion 24 in which are formed notches 25, 25 adapted to engage screw threaded posts 26, 26 carried by the frame members 7 and to be secured thereto by clamping and spacing nuts 27, 27. Secured to the plate 23 at the extreme end of the portion 24 is a fanning strip 29 under which one end of each of the conducting wires 8, 8, 9, 9 and 10, 10 is passed and looped back in a loop 30 which is offset to stiffen it in all directions, whereby a convenient and rewirable terminal is provided for connection with other conductors of a system. The offset or stiffening is obtained by passing the ends of the wires under the fanning strip, looping them in a direction 100 perpendicular to the plane of the wires and brought back under the fanning strip in the same plane as the plane of the wires.

Secured to each of the supporting plates 23 are a plurality of stiffened supporting lugs 32, 32, each provided at its ends with internally screw threaded projections 33, 33 adapted to be engaged by screws 34, 34 extending through openings 35, 35 through the side frame members 6, 6. The openings 110 35, 35 through the side frame members 6, 6 are sufficiently large to allow some clearance between the screws 34, 34 and the surrounding metal, and lock nuts 36, 36 are provided for the screws. By means of the screws 115 34, 34 the strips 5, 5 may be adjusted to any desired lateral position while the clearance between the openings 35, 35 and the screws 34, 34 permits the adjustment of the strips 5, 5 both longitudinally and horizontally.

120 In Figs. 7 and 8 there are indicated two brush sets 37 and 38 and it will be noted by reference to these drawings that the relative widths of the brushes and contact surfaces 20, 20 is such that two brushes may operate 125 simultaneously from opposite directions over the same contact surfaces without interference between the brushes. By reason of this construction a large number of brush operating mechanisms may be utilized in a 130

smaller space than would otherwise be possible. The strips 5, 5 are preferably mounted with the contact surfaces on the underside thereof so that dust and metal particles will not accumulate between the conductors, thereby reducing to a minimum the liability of trouble from such a source.

The brush operating mechanism, which is illustrated in detail in Figs. 1 to 6 inclusive, is designed to move the brushes step by step to the several levels of multiple contact strips 5, 5 and transversely thereof to selected contacts of a strip. As shown in the drawings, 5, 50, 50 designate brushes mounted upon a carriage 51 which is secured to a shaft 52. The shaft 52 is slideable in guide members 53 and 54 on a frame plate 55. Located adjacent to the shaft 52 is a toothed bar 56 adapted to be engaged by a stepping pawl 57 carried by an armature 58 of a stepping magnet 59. The toothed bar 56 is supported by collars 60 and 61 which are slideable upon the shaft 52, but there is secured to the shaft 52 a spring-pressed locking member 62 adapted, 25 in the normal position of the shaft 52 and the toothed bar 56, to engage a notch 63 in said toothed bar 56 to lock it to said shaft 52. In the first movement of the apparatus in response to impulses through the stepping magnet 59 the pawl 57 will engage the toothed bar 56 to move said bar 56 and the shaft 52 upwardly in steps equal in length to the distance between two successive teeth on the bar 56. Each of these steps will be 30 equal to the vertical distance between adjacent multiple contact layers and will continue until the brushes 50, 50 have been moved into a position opposite a desired layer. At the cessation of the first series of impulses through the stepping magnet 59 a side-switch magnet 65 will be caused to operate. This magnet by its armature 66 and a pawl and ratchet connection 67, 68 controls the 35 operation of a cam disk 69. This cam disk 69 has three sets of surfaces, each set adapted to control a switch movement through a complete cycle of operations in one complete rotation of the said disk 69. Normally an antifriction roller 70 secured to a pivotal 40 lever 71 rests in an opening 72 between adjacent sets of surfaces. At the first operation of the magnet 65 a sloping cam surface 73 will be moved under the roller 70 to push the lever 71 outwardly; at the second step 45 of the magnet 65 a straight surface 74 will be moved under the roller 70 to hold said lever 71 in its outward position; at the third step a sloping surface 75 will be moved under the roller 70 to swing said lever 71 inwardly again and bring the roller into an 50 opening 76 between cam surfaces of the same set; the fourth step of the magnet 65 will bring a cam surface 77 over the roller 70 to swing said lever 71 inwardly from a normal 55 position and the next and last movement in 60

a cycle of the cam disk 69 will bring another opening 72 between adjacent sets of cam surfaces. A projecting lug 80 on the cam disk 69 is adapted as said disk is rotated to engage a forked pivotal arm 81 to operate side-switch contacts 82, 82 over contacts 83, 84, 85, 86 and 87. 70

After the cessation of the first set of impulses through the magnet 59 by means of which the brushes 50, 50 were raised to the desired level, magnet 65 will be actuated to cause the cam disk 69 to be advanced one step by the ratchet and pawl mechanism 67 and 68. This first step of the cam disk 69 brings the surface 73 under the roller 70 and swings the lever 71 outwardly. This movement of the lever 71 causes an extension 88 thereon to act upon a roller 89 carried by an extension 90 of the locking member 62 to move a projection 91 thereon out of engagement with the notch 63 on the toothed bar 56 and a second projection 92 thereon into engagement with a notch 93 of a notched locking bar 94. This releases the shaft 52 from the toothed bar 56 and locks said shaft against further movement so that subsequent operations of the stepping magnet 59 will advance only the toothed bar 56. The lever 71 is pivotally mounted upon a rod 95, upon which is also pivotally supported a bracket member 96 having a projecting lug 97 thereon normally projecting through an opening 98 in the armature 58 of the magnet 59. When the lever 71 is moved forward the bracket member 96 is placed under a turning tension by a spring 99 (see Fig. 1) and is only prevented from turning by reason of the engagement by the lug 97 thereon with the opening 98 in the armature 58 which is in its lowermost position due to the deenergization of the magnet 59 prior to the operation of the magnet 65. Now the first one of the succeeding impulses through the stepping magnet will cause the bar to be raised a distance equal to the distance between two successive teeth but immediately after it is raised the bracket member 96 will be turned through a sufficient angle to bring the projecting lug 97 thereon into a position where it will be engaged by the lower surface of the armature 58, thereby limiting the downward movement thereof to half of the distance of its downward movement before. This first long step of the toothed bar 56 will operate a bell-crank lever 100 to move the brush carriage 51 in a direction at right angles to the shaft 52 and through a distance equal to the distance between two successive teeth on the bar 56. This first step of the brush carriage 51 is sufficient to bring the brushes 50, 50 into engagement with contacts in the first row of the selected strip 5. The succeeding steps of the bar 56, however, in response to impulses through the magnet 59 will, due to the interposition of the lug 130

97 below the armature 58, be only half as long as the steps resulting from the impulses of the first series and the first impulse of the second series so that the subsequent movement of the brushes 50, 50 will be only the distance between successive sets of contact surfaces. A sufficient number of current impulses of the second series will be sent to move the brushes 50, 50 into engagement 5 with a selected set of terminals in the strip selected by the first series of impulses. Upon the cessation of the second series of impulses the magnet 65 will be again energized to cause the movement of the cam disk 10 one step farther. This step will bring the straight surface 74 under the roller 70 and will move the side-switch wiper 82 from contacts 84 where it was previously set. The positioning of the cam surface 74 under 15 the roller 70 has no further effect upon the positions of the brush-operating parts, but the movement of the wipers 82 on to the contacts 85 may place the switch in ringing position. At the end of the ringing a third 20 energization of the magnet 65 may take place to move the wipers 82 into engagement with the contacts 86 and the cam surface 75 under the roller 70. The engagement of the cam surface 75 with the roller 70 has no 25 effect upon the operated parts of the brush mechanism except to permit the lever 71 to move back to normal position ready to pass through the opening 76 into engagement with the cam surface 77. The parts will remain 30 in the position with the wipers 82 in engagement with the contacts 86 during the conversational period, at the end of which time the operation of making a disconnection will cause another energization of the 35 magnet 65 to advance the cam 69 another step. This last step of the cam will move the cam surface 77 over the roller 70 and the wipers 82 onto the contacts 87. The movement of the cam surface 77 on to the 40 roller 70 swings the lever 71 backwardly until a finger 104 thereon engages a finger 105 on a bracket member 106 pivoted upon the rod, and which carries a holding pawl 107, normally adapted to engage the teeth 45 of the toothed bar 56 to retain it in its elevated position. The backward movement of the lever 71 carries with it the pivotal bracket member 106 to release the holding pawl 107 from the bar 56. This will cause 50 the bar 56 to drop by gravity and cause the brush carriage 51 to move outwardly, assisted by a spring 103, to draw the brushes 50, 50 clear of the contact strips 5, 5. As 55 the bar 56 moves downwardly the shaft 52 remains locked by reason of the fact that the projection 91 on the member 62 engages one face of the bar 56 to retain said shaft locked through the engagement of the projection 60 92 with the bar 94. As soon, however, as the 65 bar 56 has reached a position in its down- ward movement when the projection 91 on the locking member 62 can enter the notch 63 the shaft 52 will be unlocked from the bar 94 and locked to the toothed bar 56 so that both will drop together to normal position. 70 The backward movement of the lever 71 moves the bracket member 96 around its pivot to bring the projecting lug 97 thereon into the opening 98 through the armature 75 80 85 90 95 100 105 110 115 120 125 130 135 140 145 150 155 160 165 170 175 180 185 190 195 198 200 205 210 215 220 225 230 235 240 245 250 50 into position to engage contacts in the level with which switching apparatus associated with the subscriber B may be connected. In the particular instance, we will 5 assume that contacts in the fourth level of the contact strip 5, 5 are sought, in which case four impulses will be sent from station A. These impulses open the circuit of the relay 115 to cause it to intermittently close 10 its back contact 121 which completes a circuit for a slow-release magnet 131 in series with the stepping magnet 59 of the selector switch 120, which circuit includes side-switch wiper 132 in its first position. Relay 15 131, in pulling up, closes its contact 133 to complete a circuit from ground through side-switch wiper 134 and the side-switch magnet 65. The relays 123 and 131, both being of the slow-release type, will hold up 20 during the sending of impulses. The stepping magnet 59, however, will respond to the impulses resulting from the opening and closing of the contact 121 to step the toothed bar 56 and with it the shaft 52 and 25 brushes 50, 50 upwardly in steps of a length equal to the vertical separation of the layers 5, 5. At the end of the fourth step or impulse from the station A, the relay 115 will remain energized and open the circuit of the relay 30 131 at contact 121, causing it to drop back and open the circuit of the side-switch magnet 65 at the contact 133. The armature 66 of the side-switch magnet 65, in releasing, steps the cam 69 from its first into its second position, and moves all of the side-switch wipers from their first to their second position. The 35 movement of the cam 69 from its first into its second position unlocks the shaft 52 from the toothed bar 56 and locks it to the bar 94. 40 Also it places the bracket member 96 in condition such that the projection 97 will be moved under the stepping armature 58. As soon as the side-switch wiper 132 is moved from its first to its second position, a circuit 45 will be completed for the stepping magnet 59 which may be traced from ground through a front contact 136 of test relay 124, armature 58 of stepping magnet 59, a contact 147 in said armature, side-switch wiper 132 in its 50 second position, and through the magnet 59 to battery. This circuit will exist so long as the relay 124 is retained energized. Upon the first horizontal step of the brushes 50, 50, however, the horizontal off-normal contact 55 127 will be opened to transfer the holding circuit of relay 124 to the shortest brush 50 of the set which constitutes the test brush. The first horizontal step of the brushes 50, 50 will be a long one, as hereinbefore described, and will bring said brushes into engagement with the first set of contacts 8, 9 and 10 of the layer. If any of the contacts of this set have been taken for use by another switch, there will be a ground on the contacts 60 10, which will hold the relay 124 energized until the stepping magnet 59 has made another step. This stepping operation will be continued until the brushes 50, 50 land on a set of contacts, the contact 10 of which is not grounded. When this occurs, the circuit for the test magnet 124 will be opened, which will cause it to open the stepping magnet circuit. At the time that the side-switch wipers moved from their first to their second position, the wiper 134 completed an 65 energizing circuit for the side-switch magnet 65 from a contact 137 on the relay 124, which caused it to draw up its armature 66. As soon as relay 124 becomes deenergized, by reason of the brushes 50, 50 landing on idle 70 contacts, this last traced circuit will be opened and the armature 66 will release to move the cam 69 from its second to its third position and all of the side-switch wipers from their second to their third position. In their third positions, the wipers 116, 117 connect the circuit of station A with conductors 140, 141 leading to the longest and middle brushes 50, 50. This connection includes contacts 142, 142 of a relay 143 75 which is energized over a circuit including the front contact 129 of the relay 123. The relay 115 is retained in bridge of the line of station A and so remains until the completion of the conversation and the subscriber A hangs up his receiver to break the circuit of his line. When this occurs, relay 115 releases, opening the circuit of relay 123 80 at contact 122, causing said relay 123 to release to close its back contact 128. The closure of contact 128 completes an energizing circuit for the side-switch magnet 65 which includes a side-switch wiper 145 in its third position, and an interrupting contact 149 on the armature 66 of the side-switch magnet 85 90 95 100 105 110 115 120 125 130

What is claimed is:

1. In a switching mechanism, a bank comprising a plurality of superimposed flat multiple contact units, each of said units comprising a plurality of sets of conductors, contact surfaces on said conductors situated in rows transversely of said units, contact brushes adapted to be directively moved in one direction into juxtaposition with said units individually and further moved in a second direction transversely of said units to hunt over said conductors and engage any of the said sets of conductors in a selected unit individually.
- 15 2. In an automatic switch, a contact member adapted for separate movements of different length steps in different directions and a single step-by-step mechanism adapted to transmit the separate movements to said contact member.
- 20 3. In an automatic switch, a contact member adapted to be moved in a straight line in steps of one length and in a direction at right angles to the first mentioned movement in steps of a different length, and a single step-by-step mechanism for transmitting the two movements to said contact member.
- 25 4. In an automatic switch, a carriage, a contact member adapted to be moved in one direction by the movement of said carriage and in a different direction independently of said carriage, an operating mechanism for moving said carriage, and means for disengaging said operating mechanism from said carriage to permit it to move said contact member independently of said carriage.
- 30 5. In an automatic switch, a longitudinally movable rod, a contact member carried by said rod and movable independently thereof, a toothed member normally connected with said rod, an operating connection between said toothed member and said contact member, and means for disconnecting said rod from said toothed member whereby the continued operation of said toothed member will operate only said contact member.
- 35 6. In an automatic switch, a longitudinally movable rod, a toothed rack slidable upon said rod but normally locked thereto, a contact carriage mounted upon said rod and movable therewith, a contact on said carriage movable independently of said rod, a connecting link between said toothed rack and said contact, and means for disconnecting said rack from said rod whereby a further movement of said rack will move said contact member independently of said rod.
- 40 7. In an automatic switch, a longitudinally movable rod, a contact carriage carried by said rod, a contact member on said carriage movable independently of said rod, a common operating means for said rod and said contact member, and means for render-
- 45 ing said operating means effective with respect to said contact member and ineffective with respect to said rod.
- 50 8. In an automatic switching system, a plurality of contact members each comprising a plurality of longitudinally extending conductors arranged in the same plane, each conductor being provided with a plurality of contact surfaces spaced longitudinally thereof, and a plurality of independently movable switches located upon opposite sides of said contact member each adapted to be moved at right angles to the planes of said members and parallel thereto to make contact with any set of conductors in any of said contact members.
- 55 9. In an automatic switching system, a contact bank comprising a plurality of fabricated multiple contact members mounted in superimposed relation equal distances apart, each of said contact members having sets of contact surfaces extending in lines transverse of said members, and spaced apart a distance less than the spacing of adjacent multiple contact members, and brush sets adapted to be moved perpendicular to the planes of said contact members in steps equal in length to the distance between terminal members and in a direction transverse to said members in steps equal to the transverse distance between contacts of adjacent contact surfaces.
- 60 10. In an automatic switch, stationary contact members, a movable contact member adapted to be moved in two distinctly separate movements into engagement with stationary contact members, a single step-by-step mechanism for transmitting the separate movements to said movable contact member, mechanical means for determining the change-over from one character of movement to the other and for controlling the release of said movable contact member after operation, a circuit controlling switch operated by said mechanical means, and an electromagnet for controlling said mechanical means.
- 65 11. In an automatic switch, stationary contact members, a movable contact member adapted to be moved in series of steps of different lengths into engagement with stationary contact members, a single step-by-step mechanism for transmitting to the movable contact member the series of steps of different lengths, a mechanical means for determining the change-over from steps of one length to steps of the other length, a circuit controlling switch operated by said mechanical means, and an electromagnet for controlling said mechanical means.
- 70 12. In an automatic switch, stationary contact members, a movable contact member adapted to be moved in two directions and in steps of different lengths into engagement with stationary contacts, a single step-by-

step mechanism for transmitting to the movable contact member the separate series of steps, mechanical means for determining the change-over from steps of one series to 5 steps of the other series, a circuit controlling switch operated by said mechanical means, and an electromagnet for controlling said mechanical means.

13. In a switching mechanism, a contact bank comprising a plurality of superimposed flat multiple contact strips, a plurality of sets of conductors extending longitudinally of said strips, contact surfaces on said

conductors disposed on the under sides of said strips and situated in rows transversely 15 thereof, contact brushes adapted to be directly moved in one direction into juxtaposition with said strips individually and further moved in a second direction transversely of said strips to hunt over said conductors and engage any of said sets of conductors in a selected unit individually.

In witness whereof, I hereunto subscribe my name this 27th day of March, A. D. 1917.

JOHN NEWBERRY REYNOLDS.
